UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,807, dated May 16, 1899.

Application filed April 6, 1899. Serial No. 712,021. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part thereof, in which—

Figure 1 is a top or plan view of a manhole-cover embodying my design, and Fig. 2 is a cross-sectional view on the line $z z$ of Fig. 1.

The views are deemed essential or necessary to a proper illustration and understanding of the design of my invention.

The leading feature of my design for a manhole-cover consists of the shape or configuration of the cover.

Referring to the drawings, a represents the cover, which viewed in plan is circular in form, with a convex-shaped bottom a' and a

right-angular surrounding wall a^2 , as illustrated in Fig. 2. The exterior surfaces forming the right-angular wall a^2 flare outwardly, and the interior surface of said wall as to the lower portion a^3 flares outward, and there is formed a ledge a^4 between the lower and upper portions on the inner side of the cover, and the upper portion of the said wall on the inner side is beveled, as at a^5 in Fig. 2, to the top of the cover.

Having thus described my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.

Witnesses:

J. WALTER DOUGLASS,
THOMAS M. SMITH.
